UNITED STATES PATENT OFFICE.

HERBERT H. STEELE, OF BROOKLYN, NEW YORK, ASSIGNOR, BY MESNE ASSIGNMENTS, TO JOHN H. EGGERS COMPANY, INC., OF NEW YORK, N. Y., A CORPORATION OF NEW YORK.

COIN-CARD AND METHOD OF MAKING THE SAME.

1,398,607.

Specification of Letters Patent.

Patented Nov. 29, 1921.

Application filed April 12, 1916. Serial No. 90,795.

To all whom it may concern:

Be it known that I, HERBERT H. STEELE, a citizen of the United States, residing at Brooklyn, in the county of Kings and State 5 of New York, have invented new and useful Improvements in Coin-Cards and Methods of Making the Same, of which the following is a specification.

My invention relates to coin-mailing-cards, or cards adapted to retain any of the 10 coins found in general circulation, to prevent them from shaking loose in the envelop in transit through the mails.

The object of my invention is to provide 15 an improved coin card and also to improve the method of manufacture over that disclosed in my prior application filed July 29th, 1915, Serial Number 42,583. In my prior application, pasting elements are 20 shown and described whereby one of the webs of paper may receive a surface coating of paste or glue, except at the positions of the coin-pockets previously formed in one web, so that when the two webs are joined 25 together under pressure, the tongue or strap extending across each coin-pocket, may be readily raised away from the adjoining face of the under web as when a coin is introduced under the strap and forced into the

30 coin pocket. It was found in practice, however, that while a coin card so constructed was practical in every way, there were certain features associated with this wet process of pasting, that were objectionable. First, 35 that if for any reason the machine was stopped for a moment, the paper web that received the surface coating of paste, would become stuck to the face of the paste-distributing roller and the web usually had to

40 be torn loose or loosened from the said roller by the application of water before the machine could be started. Second, that when the machine was stopped for the night, the paper webs and all the glue-distributing 45 elements had to be removed from the machine and washed and again assembled in the machine in the morning. And third, a very serious objection was the buckling or curling of the finished coin card, due to the

50 unequal contraction between the thin moist web of paper and the thicker web of cardboard in drying. Furthermore, the underside of the finished card is more or less damp as it comes out of the machine and the tend-

ency is to smear the freshly printed face of 55 the adjoining card in the pile and more especially so if the cards are placed in a press to flatten them until dry.

In accordance with my present invention, the thinner web or backing paper for the 60 coin card is previously given a surface coating of adhesive mixture and allowed to dry before it is employed in the manufacture of the coin card. This is preferably done in a 65 separate machine adapted to take in a very wide web of paper and after the adhesive face has become dry and all contraction in the paper has ceased, this wide web may be slit into narrower webs adapted for the coin card and rolled into convenient rolls for the 70 machine.

In the present instance, all the glue distributing devices shown in my prior application are discarded. In their place, a trough is arranged under the former distributing cylinder that came into contact with one web and this trough is partially filled with water, so that the surface of this cylinder may rotate in a water bath and transfer the required amount of moisture to 80 the face of the associated web, instead of paste as heretofore.

By a dry process of this character, the finished coin cards are practically dry as they 85 emerge from the machine; they do not smear each other when piled together and there is no contraction of the paper to cause the finished card to curl or buckle; and coin cards so manufactured, may be taken immediately 90 from the machine and packed into shipping 95 boxes without danger of smearing the printed faces, as heretofore. Furthermore, as the pasting operation in the machine consists of nothing more than moistening a surface of one web that subsequently is brought into contact with the dry adhesive surface of the other web, it will be seen that the machine may be stopped at will without any of the parts becoming stuck to the web; and there is nothing to clean at night and nothing to 100 reassemble in the morning; the water bath of the cylinder keeping the surface clean and preventing the accumulation of paper-sizing dust from forming ruts and ridges on the surface of the cylinder to disfigure the cards 105 and seriously interfere with the proper execution of the printing elements to give clean, uniform impressions.

In the drawing forming part of this application, Figure 1 is a plan view of the underside of the cardboard section of the coin card; the dotted lines indicating the field 5 around each pair of perforations where no water is applied to the back of the card.

Fig. 2, is a plan view of the paper web, or 10 backing strip, showing the entire face covered by an adhesive mixture that has been previously allowed to dry.

Fig. 3, is a plan view of the finished coin card, showing the dry gummed face of the backing sheet or strip through the perforations made in the cardboard section to 15 retain the coin.

Fig. 4, is a section indicated by the line α, α , of Fig. 3, to better illustrate the sections of the two webs that are stuck together and the sections immediately surrounding the 20 coin cavities that are not joined together, so that the tongue or strap extending across each coin cavity, is free to be raised away from the surface of the backing paper.

Fig. 5, is a diagrammatic view illustrating 25 in consecutive order, the several operations the webs pass through until the finished coin card is severed.

Fig. 6 is a view of a section of the distributing roller that conveys moisture to the 30 face of one web to soften or dissolve the adhesive element when the two webs are brought together under pressure, and also shows the manner of applying this moisture to the surface of one web and still leave dry 35 areas that will not adhere to the gummed surface of the other web.

In Figs. 1 and 2, a card is shown having two coin pockets; one adapted for a twenty-five cent and the other for a fifty-cent coin. 40 These pockets differ only in size and each comprises two arc-shaped perforations 1 and 2 that are separated by a tongue or strap 3, formed integrally with the cardboard section 4. Each perforation 1 and 2 is formed 45 with round terminals 5 that continue the arc-shaped perforations to points beyond the radius of the arc of the coin cavity to give the aforesaid strap greater flexibility by increasing its length which otherwise, would 50 be limited by the actual diameter of the coin.

The backing paper 6, is a previously 55 gummed tape or strip having a width suitable for the card 4 and cut the same length. The back of the cardboard member 4 may 60 be moistened in any suitable manner so as to leave the sections inclosed by the dotted lines 4^a dry. The backing paper 6 is laid with the adhesive down, over the moistened back of the card 4 and pressed down as by 65 rubbing the hand over the entire surface. This will cause the two paper elements to adhere, but the sections within the dotted lines 4^a of Fig. 1, being dry, will not stick 70 to the surface of the gummed sheet 6 and

the tongue 3 is free to be raised when a coin is introduced into the pocket or cavity formed by the two arc-shaped perforations. The glued and unglued portions are shown exaggerated at Fig. 4, the gum or paste being 70 indicated at 7. Where the gum adheres to the back of the card 4, said gum is shown in heavy black, but where the gum does not adhere it is shown by dotted or stippled portions 7^a. It will be noted that the free or 75 unattached parts represented by the stippled portions 7^a are under the strap and disk portions 3—8, where no moisture was applied.

To render the operation of inserting a coin under the strap 3 as easy as possible, 80 the said strap is formed with a disk-shaped center 8, which forms a lip on either side of the strap, that may be more readily raised than though the strap was of uniform width across the coin pocket. In a coin card thus 85 constructed, when the coin is forced under the strap 3—8, it falls into a pocket formed by the curved edges of the cardboard, is prevented from falling out through the bottom by the backing piece 6 and held securely 90 within the pocket by the said strap extending across the face of the coin.

In cards providing twenty-five and fifty-cent pockets as shown at Figs. 1 and 3, it 95 may be desirable at times to send coins of a smaller denomination, such as nickels or dimes. These coins being smaller than the coin pockets provided in the card, to insure a safer transmission, the coin itself may be moistened on its back before it is placed in 100 the pocket under the strap, which will cause the moistened face of the coin to adhere to the surface of the backing paper 6, which at this location is provided with exposed dry adhesive material adapted to be softened or 105 dissolved by the wetted or moistened coin thus inserted. In this use of the card, it will be noted that the coin is not only held by the tension of the strap itself but also by the gummed portion thereunder, thus making 110 doubly sure that the coin will not become detached in transit or in rough handling. Moreover, even when the coin is not itself moistened on the back as stated, the presence 115 of the rough gummed section in register with the strap tends to assist the action of the strap in holding the coin against lateral displacement.

While I have described the coin card and the method of making a single card by hand, 120 I prefer to manufacture them in large quantities by a special method of manufacture, shown diagrammatically in connected series at Fig. 5, where 4 indicates a roll of cardboard and 6 a roll of previously prepared 125 gummed and dried tape of paper both of uniform width. The card board 4 as it passes from the roll passes between punches and dies 11 and 12 and the perforations 1 and 2 are made. The cardboard then passes 130

between the two rollers 13 and 14; the roller or cylinder 13 being provided with holes or gaps 15 that are timed to align with the perforation 1 and 2 as the cardboard is drawn 5 through. A tank or trough 16 is provided and partly filled with water so that the enter face of the cylinder 13 will become moistened in rotating through this water bath. The gummed dry paper 6 passes from 10 the roll over two guide rolls 17 and is brought to bear with the gummed surface up, against the moistened underside of the cardboard web 4. Both webs 4 and 6 then pass between the two pressure rollers 18 and 15 are caused to adhere together under the pressure of said rollers which latter also operate to draw both webs from their rolls. The joined webs then pass under the electro- 20 plates 19 where the exposed face or surface of the cardboard is given type impressions; the web then passes to the reciprocating cutters 20 where the finished printed card is severed from the web. From this description, it will be seen that the operation of 25 punching, pasting, printing and cutting, are continuous operations; the several mechanisms being so timed relative to one another, that two complete products are turned out at every complete revolution of the web- 30 feeding rollers 18, in precisely the same manner as described in my prior application previously referred to.

From this diagrammatic lay-out, it will be seen that there is no contact whatever 35 between the adhesive element and the moistening element; that the machine may be stopped at will to replace either a roll of cardboard or paper without any interference from the gummed dry face of the pa- 40 per 6; that the amount of moisture applied or transferred to the underside of the cardboard 4 may be regulated by increasing or diminishing the pressure of the roller or cylinder 14 against the upper face of the 45 cardboard.

Having fully described the nature of my invention, I desire to secure the same by Letters Patent and therefore claim—

1. The method of making a coin card con- 50 sisting first in forming one or more open- ings in the card, secondly in moistening the back of the card, and thirdly in applying to the moistened back under pressure, a

strip of previously prepared dry adhesive material in such a manner as to bridge the 55 coin opening or openings.

2. The method of making a coin card con- 60 sisting first in forming in the card one or more openings comprising each a strap, sec- 65 ondly in moistening the back of the body of the card without moistening the back or backs of the strap or straps, and thirdly in pressing on the moistened back of the body of the card, a strip of previously pre- 70 paried dry adhesive material in such a man- 75 ner as to bridge the coin opening or open- 75 ings and yet be unattached to the said strap or straps.

3. The method of making a coin card con- 70 sisting first in forming one or more open- 75 ings in the card, secondly in moistening the back of the card, and thirdly in applying to the moistened back under pressure a strip of previously prepared material having a 80 dry adhesive on one side thereof, in such a 85 manner as to bridge the coin opening or open- 90 ings.

4. The method of making a coin card con- 80 sisting first in forming one or more open- 85 ings in the card, secondly in moistening the back of the card excepting at the coin hold- 90 ing positions or portions, and thirdly in ap- 95 plying to the moistened back under pressure a strip of previously prepared dry adhesive material that covers the entire back of the 95 card and yet is unattached at the coin hold- 100 ing positions.

5. The method of making a coin card con- 90 sisting first in forming in the card one or more openings comprising each a strap, sec- 95 ondly in moistening the back of the body of the card without moistening the back or backs of the strap or straps, and thirdly in pressing on the moistened back of the body of the card, a strip of previously prepared material having a dry adhesive surface, in such a manner as to bridge the coin open- 100 ings and yet be unattached to the said strap or straps.

In testimony whereof I have signed this 100 specification in the presence of two subscrib- ing witnesses.

HERBERT H. STEELE.
